VENTILATED SHOE

John W. Meaker, Evanston, Ill.

No Drawing. Application January 25, 1940,
Serial No. 315,526

3 Claims. (Cl. 36—3)

This invention relates to leather shoes, boots or other similar footwear, which will be collectively referred to herein as "shoes"; and the primary object of the invention is to provide a shoe with a relatively large number of widely distributed, minute, artificially formed perforations which, while permitting free passage of air into and out of the shoe under conditions of wear, are small enough to substantially exclude water, which are, preferably, invisible or substantially so, and which do not substantially impair the strength of the leather.

The degree of ventilation may be varied by varying the size of the perforations which may be as small as $\frac{1}{500}$ inch in diameter or even smaller; or by varying the number of perforations per unit area which, merely as examples, may vary from 10 or 20 to 100 or more in number per square inch.

The perforations may be made by causing electric arcs to pierce the leather at suitable intervals, and any suitable machinery may be used for the purpose. For example, the leather may be run between rollers provided with electrodes forming spark gaps through which the leather passes as disclosed for example in U. S. Patent No. 1,790,452, granted to Irvin H. Wilsey January 27, 1931. Variation of current intensity will cause variation in the size of the perforations and the number of perforations per unit area may be varied by varying the number of the spark gaps or the speed of the material therethrough. The present invention is not concerned with the particular apparatus used.

The perforations are formed by electrically perforating the leather. Hence, they are burrless in distinction to pricked holes which if small are likely to close up with pressure.

Various expedients have been employed heretofore for ventilating shoes but all have disadvantages. Air has been let into the shoes through ducts arranged in various places. Rubber cushions have been put into the soles which by compression and expansion pump air into the interior of the shoes. It has been common also to punch holes in the uppers. These holes are frequently about one-sixteenth of an inch in diameter. They destroy the waterproof character of the leather. They are more or less unsightly. They

detract from the warmth of the shoe in winter and from the strength of the leather. Ordinary polishes cannot be used without entering the holes and soiling the hosiery and the feet.

In carrying out the present invention, the hides may be perforated by the electric arcs; or the shoe parts for example the parts constituting the upper after being cut; or, less conveniently, the shoes after they have been manufactured or during manufacture at any stage.

The electric arc formed perforations will not admit water. Nor will they admit the ordinary polishes. These when applied cover the perforations, but as the shoes are worn and flexed with walking, the perforations open up and fulfill their ventilating function.

The cost of the perforation operation is very slight. The strength of the leather is not substantially impaired. The perforations are not visible except possibly on close inspection and then are not recognizable as perforations. Generally speaking, the ventilation is effected without materially changing the appearance of the shoes.

I claim:

1. A shoe the upper of which is composed of leather formed with a plurality of minute, burned, burrless perforations which, while permitting the free passage of air in and out of the shoe while the shoe is being worn, are small enough to exclude water, whereby the shoe though ventilated is substantially waterproof.

2. A leather shoe provided with a plurality of widely distributed, minute, electric arc burned, burrless perforations which, while permitting free passage of air into and out of the shoe under conditions of wear, are small enough to substantially exclude water, whereby the shoe is ventilated without substantial impairment of its water proof character.

3. A leather shoe provided with a plurality of widely distributed, minute, electric arc burned, burrless perforations which, while permitting free passage of air into and out of the shoe under conditions of wear, are small enough to be substantially invisible and to substantially exclude water, whereby the shoe is ventilated without appreciable change in appearance or substantial impairment of its water proof character.

JOHN W. MEAKER.
